[57] ABSTRACT

The disclosure teaches a group of carbamoylphosphonamides can be used to retard the growth of plants.

The carbamoylphosphonamides of this invention are prepared as follows. An appropriate amine is reacted with a halogenated phosphite. The product is treated with a suitable halogenated carboxylic acid ester followed by treatment with ammonia or a suitable amine.

PHOSPHONAMIDE PLANT GROWTH REGULANTS

CROSS-REFERENCE TO RELATED APPLICATION

This application is a continuation-in-part of my co-pending application Ser. No. 79,252, filed Oct. 8, 1970, now U.S. Pat. No. 3,712,936.

SUMMARY OF THE INVENTION

This invention relates to a novel group of carbamoyl phosphonamides, the method of using the carbamoyl phosphonamides to modify plant growth patterns and formulations containing the carbamoylphosphonamides which are useful in plant modification applications.

The compounds of this invention are represented by the following formula:

where

R is alkyl of from one to eight carbon atoms, chloroalkyl of from one to eight carbon atoms containing up to three chlorine atoms, bromoalkyl of from one to eight carbon atoms containing up to three bromine atoms, alkoxyalkyl of from three to ten carbon atoms, alkenyl of from two to eight carbon atoms, alkynyl of from three to four carbon atoms, phenyl of benzyl;

R_1 is hydrogen, alkyl of one to four carbon atoms, hydroxyalkyl of two to four carbon atoms, alkenyl of three to four carbon atoms, or alkynyl of three to four carbon atoms;

R_2 is hydrogen, alkyl of one to four carbon atoms, hydroxyalkyl of two to four carbon atoms, alkenyl of three to four carbon atoms, or alkynyl of three to four carbon atoms; or R_1 and R_2 can be taken together to form a bridge consisting of $-(\text{CH}_2)_2-\text{O}-(\text{CH}_2)_2-$ or $(\text{CH}_2)_n$ where n is 4, 5, or 6; and one of R_1 and R_2 can be

where R_5 and R_6 are the same or different and are hydrogen or alkyl of one through four carbon atoms;

R_3 is hydrogen, alkyl of one to four carbon atoms or alkenyl of three to four carbon atoms; and R_4 is hydrogen, alkyl of one to four carbon atoms or alkenyl of three to four carbon atoms.

5 Of the above compounds of formula 1, those compounds where R is alkyl of one to four carbon atoms or alkenyl of two to four carbon atoms, R_1 and R_2 are each hydrogen and R_3 and R_4 are each hydrogen or alkyl of one to four carbon atoms are preferred because of their outstanding activity.

10 This invention also relates to the method of modifying the growth rate of plants which comprises applying an effective amount of a compound of formula (1) to a plant to effect modification of the growth of said plant, particularly retardation of the growth rate of treated plants, especially that of woody vegetation.

15 This invention further relates to agricultural formulations consisting of a compound of formula (1) in combination with suitable agricultural adjuvants and modifiers.

DESCRIPTION OF THE INVENTION

20 This invention is founded on the discovery that the compounds of formula (1) are useful for modifying the growth rate of plants. In this regard, it has been noted that the compounds of this invention, as represented by formula (1), are particularly useful to retard the growth rate of plants. The compounds of this invention are particularly useful to retard the growth of woody plants. 25 The compounds of this invention can, therefore, be applied in areas such as power line rights-of-way where low-growing and slow-growing vegetation is especially desirable. They are useful to control the growth and flowering of ornamental species such as chrysanthemum and azalea.

30 The compounds of this invention can also be used to prolong the dormancy of perennial plants by the delay or prevention of bud break in the spring.

Preparation

35 The carbamoylphosphonamides of this invention are readily prepared by the interaction of an appropriate amine with a halogenated phosphite followed by treatment with an appropriate halogenated carboxylic acid ester and then ammonia or an amine.

40 These reactions can be represented as follows:

In the above equations, R , R_1 , R_2 , R_3 and R_4 are defined as above. R_7 is lower alkyl, preferably methyl or

ethyl. X is oxygen or sulfur. Normally, X will be oxygen, in the above described reaction, however, when the amine in equation 4 has relatively low reactivity, X is preferably sulfur. More information relative to the reaction when X is sulfur can be had by reviewing the disclosure of U.S. Pat. No. 3,005,010.

The starting materials of equation 2, above, are commercially available or can be readily prepared using methods known to the art. The reaction of equation 2 is run at approximately 0°C. and involves a slow addition of the amine to a solution of the dialkyl chlorophosphite in an inert solvent. Suitable solvents include ethers, hydrocarbons or chlorinated hydrocarbons.

The phosphoramidite ester intermediates are generally liquids and may be purified by distillation under reduced pressure after removal of the amine hydrochloride by-product and the solvent. Illustrative of the dialkyl chlorophosphite esters which can be employed in the reaction are dimethyl chlorophosphite, diethyl chlorophosphite, diallyl chlorophosphite, bis-(2-chloroethyl) chlorophosphite, and dioctyl chlorophosphite.

Illustrative of the amines useful in the above reaction are methylamine, diethylamine, diallylamine, butylamine and isopropylamine.

In the procedure outlined in reaction 3 the phosphoramidite ester is treated with a chloroformate or chlorothiolformate at a temperature of from -10°C. to 100°C. In this reaction, a solvent is not necessary, although one can be used if desired and when a solvent is used that solvent should be inert to the reactants employed. Solvents suitable for use in this reaction include ethers and hydrocarbons. The carbonylphosphonamide ester intermediates generally are liquid products. Many times, it is not necessary to purify them further after removal of the by-product alkylhalide, however, if necessary, purification can be carried out by distillation at reduced pressure. Illustrative of the acid chlorides employed in the above reaction are methyl chloroformate, ethyl chloroformate, methyl chlorothiolformate and ethyl chlorothiolformate.

Illustrative of the phosphoramidite ester intermediates which can be used as a starting material in reaction 3 are dimethyl N-methylphosphoramidite, diphenyl N-methylphosphoramidite, diethyl N,N-diethylphosphoramidite, dimethyl N,N-dipropylphosphoramidite and bis(2-chloroethyl) N,N-dimethylphosphoramidite. The procedure of reaction 4 is conducted at a temperature of from 0°C. to 25°C. The reaction can be run with or without a solvent present. Suitable solvents include water, ethers, hydrocarbons or chlorinated hydrocarbons. Illustrative of the amines which can be employed in reaction 4 are methylamine, dimethylamine, ethylamine, allylamine, 1,1-dimethylhydrazine, morpholine and pyrrolidine.

Illustrative of the carbonyl phosphonamide ester intermediates which can be employed in reaction 4 are allyl methoxycarbonyl-N-methylphosphonamidate, methyl methoxycarbonyl-N,N-dimethylphosphonamidate, ethyl methoxycarbonyl-N,N-diethylphosphonamidate, 2-chloroethyl ethoxycarbonyl-N,N-dimethylphosphonamidate, butyl methoxycarbonyl-N,N-diethylphosphonamidate, isopropyl methoxycarbonyl-N,N-dimethylphosphonamidate and octyl methoxycarbonyl-N,N-dimethylphosphonamidate.

The following are illustrative of the carbamoylphosphonamides of this invention:

Ethyl Carbamoyl-N,N-diethylphosphonamidate
Allyl Carbamoyl-N,N-dimethylphosphonamidate
Ethyl Carbamoyl-N,N-dimethylphosphonamidate
2-Chloroethyl Carbamoyl-N,N-diethylphosphonamidate

Methyl Carbamoyl-N,N-diallylphosphonamidate
Isopropyl Dimethylaminocarbamoyl-N,N-dimethylphosphonamidate

Ethyl Methylcarbamoyl-N-methylphosphonamidate

10 The compounds of formula (1) generally are liquids, but some are solids. In general, the compounds prepared according to the methods described above are acceptable for use as plant growth regulants after removal of the by-product alcohol and solvent, although 15 if further purification is desired, the solid products can be recrystallized from an appropriate solvent and those products of this invention which are liquid can be distilled under high vacuum.

Those compounds of formula (1) containing short-chain substituents in general have good solubility in water, lower alcohols and ketones. Those compounds of formula (1) with longer chain substituents exhibit decreased solubility in water, but have increased solubility in most organic solvents. The differences in physical 25 properties can be employed to advantage in the preparation of various types of agricultural formulations as will be illustrated below.

The following examples are presented to further illustrate this invention. In the example, parts and percentages are by weight unless otherwise specified.

EXAMPLE 1

35 One hundred parts of diethyl chlorophosphite are dissolved in 640 parts of anhydrous diethyl ether and treated slowly with 102 parts of diethylamine with the reaction temperature maintained at 0°C. After stirring an additional hour at 0°C., the mixture is warmed to 25°C. and the diethylamine hydrochloride is removed by filtration. Evaporation of the solvent and distillation of the residue affords 85 parts of diethyl N,N-diethylphosphoramidite, b.p. 69°-73°/9.2 mm.

40 Eighty-five parts of the above liquid are cooled to -10°C. and treated dropwise with 42 parts of methyl chloroformate over a 3-hour period. The mixture is slowly warmed to 100°C. The temperature is maintained until gas evolution ceases. Distillation of the mixture gives 55.4 parts of ethyl methoxycarbonyl-N,N-diethylphosphonamidate, b.p., 90°-92°/0.5 mm.

45 Ten parts of the above liquid are treated with 18 parts of a 29 percent solution of ammonia in water at 0°. After 30 minutes the solution is evaporated under reduced pressure affording 8 parts of essentially pure 50 ethyl carbamoyl-N,N-diethylphosphonamidate m.p. 98°-101°C.

EXAMPLES 2-44

60 The procedure of Example 1 is repeated, substituting a stoichiometric quantity of the indicated "Dialkyl chlorophosphite," the "First Amine" and the "Second Amine" to produce the "Carbamoyl Product." Alternatively, the methyl chloroformate can be replaced by a stoichiometric quantity of methyl chlorothiolformate when it is advantageous to do so.

Ex.	Dialkyl Chlorophosphite	First Amine	Second Amine	Carbamoyl Product
2	diethyl chlorophosphite	dimethylamine	ammonia	octyl carbamoyl-N,N-dimethyl-phosphonamidate
3	bis[4-(2-chloro)octyl] chlorophosphite	methylamine	ammonia	4-(2-chloro)octyl carbamoyl-N-methylphosphonamidate
4	bis[4-(1,2,3-trichloro) octyl]chlorophosphite	methylamine	ammonia	4-(1,2,3-trichloro)octyl carbamoyl-N-methylphosphonamidate
5	dipropargyl chlorophosphite	dimethylamine	ammonia	propargyl carbamoyl-N,N-dimethyl-phosphonamidate
6	dimethyl chlorophosphite	diethylamine	butylamine	methyl butylcarbamoyl-N,N-diethyl-phosphonamidate
7	bis[4-(2-bromo)octyl] chlorophosphite	diethylamine	ammonia	4-(2-bromo)octyl carbamoyl-N,N-diethylphosphonamidate
8	bis[4-(1,2,3-tribromo)octyl] chlorophosphite	diethylamine	ammonia	4-(1,2,3-tribromo)octyl carbamoyl-N,N-diethylphosphonamidate
9	bis(2-chloroethyl) chlorophosphite	diethylamine	methylamine	2-chloroethyl methylcarbamoyl-N,N-diethylphosphonamidate
10	bis(2,2,2-trichloroethyl) chlorophosphite	diethylamine	ammonia	2,2,2-trichloroethyl carbamoyl-N,N-diethylphosphonamidate
11	bis(2-chloroethyl) chlorophosphite	diethylamine	ammonia	2-chloroethyl carbamoyl-N,N-diethylphosphonamidate
12	bis(2,2,2-tribromoethyl) chlorophosphite	diethylamine	ammonia	2,2,2-tribromoethyl carbamoyl-N,N-diethylphosphonamidate
13	bis(2-methoxyethyl) chlorophosphite	dimethylamine	ammonia	2-methoxyethyl carbamoyl-N,N-diethylphosphonamidate

15	diallyl chlorophosphite	diethylamine	dimethylamine	allyl dimethylcarbamoyl-N,N-diethylphosphonamidate
16	bis(4-oct-2-enyl) chlorophosphite	diethylamine	ammonia	4-oct-2-enyl carbamoyl-N,N-diethylphosphonamidate
17	bis(3-butyanyl) chlorophosphite	diethylamine	ammonia	3-butyanyl carbamoyl-N,N-diethylphosphonamidate
18	diphenyl chlorophosphite	dimethylamine	ammonia	phenyl carbamoyl-N,N-dimethylphosphonamidate
19	dibenzyl chlorophosphite	dimethylamine	ammonia	benzyl carbamoyl-N,N-dimethylphosphonamidate
20	diethyl chlorophosphite	dimethylamine	dimethylamine	ethyl dimethylcarbamoyl-N,N-diethylphosphonamidate
21	diethyl chlorophosphite	diethylamine	diethanolamine	ethyl bis(2-hydroxyethyl)carbamoyl-N,N-diethylphosphonamidate
22	diethyl chlorophosphite	diethylamine	2-aminopropanol	ethyl 2-(1-hydroxy)propylcarbamoyl-N,N-diethylphosphonamidate
23	diethyl chlorophosphite	diethylamine	allylamine	ethyl allylcarbamoyl-N,N-diethylphosphonamidate
24	diethyl chlorophosphite	diethylamine	methylallylamine	ethyl methylallylcarbamoyl-N,N-diethylphosphonamidate
25	diethyl chlorophosphite	dimethylamine	but-2-ynylamine	ethyl but-2-ynylcarbamoyl-N,N-diethylphosphonamidate
26	diethyl chlorophosphite	diethylamine	azetidine	ethyl 1-azetidinylcarbonyl-N,N-diethylphosphonamidate
27	diallyl chlorophosphite	diethylamine	pyrrolidine	allyl 1-pyrrolidinylcarbonyl-N,N-diethylphosphonamidate
28	diethyl chlorophosphite	dimethylamine	morpholine	ethyl 1-morpholinylcarbonyl-N,N-diethylphosphonamidate
29	diethyl chlorophosphite	dimethylamine	piperidine	ethyl 1-piperidinylcarbonyl-N,N-diethylphosphonamidate
30	diisopropyl chlorophosphite	diethylamine	1,1-dimethyl-hydrazine	isopropyl dimethylaminocarbamoyl-N,N-diethylphosphonamidate
31	diethyl chlorophosphite	dimethylamine	butylhydrazine	ethyl butylaminocarbamoyl-N,N-diethylphosphonamidate
32	diethyl chlorophosphite	dibutylamine	ammonia	ethyl carbamoyl-N,N-dibutylphosphonamidate
33	diethyl chlorophosphite	butylamine	ammonia	ethyl carbamoyl-N-butylphosphonamidate
34	diethyl chlorophosphite	methylamine	methylamine	ethyl methylcarbamoyl-N-methylphosphonamidate
35	diallyl chlorophosphite	dimethylamine	isopropylamine	allyl isopropylcarbamoyl-N,N-diethylphosphonamidate
36	dimethyl chlorophosphite	diallylamine	ammonia	methyl carbamoyl-N,N-diallylphosphonamidate
37	diethyl chlorophosphite	dimethylamino	ammonia	ethyl carbamoyl-N,N-dimethylallylphosphonamidate
38	diallyl chlorophosphite	dimethylamine	ammonia	allyl carbamoyl-N,N-dimethylphosphonamidate
39	diethyl chlorophosphite	dimethylamine	ammonia	ethyl carbamoyl-N,N-dimethylphosphonamidate
40	dimethyl chlorophosphite	butylamine	ammonia	ethyl carbamoyl-N-butylphosphonamidate
41	diisopropyl chlorophosphite	dimethylamine	dimethylamine	isopropyl dimethylcarbamoyl-N,N-diethylphosphonamidate
42	dimethyl chlorophosphite	diethylamine	ammonia	ethyl carbamoyl-N,N-diethylphosphonamidate
43	dimethyl chlorophosphite	dimethylamine	ammonia	ethyl carbamoyl-N,N-dimethylphosphonamidate
44	diisopropyl chlorophosphite	diethylamine	ammonia	isopropyl carbamoyl-N,N-diethylphosphonamidate

Formulation

As stated above, one aspect of this invention relates to a formulation containing a compound of formula (1) in combination with pest control adjuvants or modifiers to provide compositions in the form of dusts, water soluble powders, solutions, granules or pellets. In addition, other plant growth modifying agents such as maleic hydrazide and "Alar" (N-dimethylaminosucci-

namic acid) can be included in the compositions of this invention in combination with the compounds of this invention.

Compositions of the invention, may contain as a conditioning agent one or more surface-active agents, sometimes called surfactants, in amounts sufficient to render a given composition containing the compounds of this invention readily dispersible in water or capable of wetting foliage efficiently.

The surface-active agent used in this invention can be a wetting, dispersing or an emulsifying agent which will assist dispersion and solution of the active compound. The surface-active agent or surfactant can include such anionic, cationic and non-ionic agents as have heretofore been generally employed in plant control compositions of similar types. Suitable surface-active agents are set forth, for example, in "Detergents and Emulsifiers" 1968 Annual by John W. McCutcheon, Inc.

In general, less than 10 percent by weight of the surface-active agent will be used in compositions of this invention and ordinarily the amount of surface-active agents will range from 1-5 percent but may even be less than 1 percent by weight.

Additional surface-active agents can be added to the formulations to increase the ratio of surfactant:active ingredient up to as high as 5:1 by weight. Such compositions may have a greater effectiveness than can be expected from a consideration of the activity of the components used separately. When used at higher rates, it is preferred that the surfactant be present in the range of one-fifth to five parts surfactant for each one part of active agent.

Water-Soluble Powders

Water-soluble powders are compositions containing the water-soluble active material, an inert solid extender which may or may not be water-soluble, and optionally one or more surfactants to provide rapid wetting and solution. A buffer, which may also function as an extender, can be present to improve formulation stability and to control the pH of the final spray solution.

The classes of extenders suitable for the water-soluble powder formulations of this invention are the natural clays, diatomaceous earth, synthetic mineral fillers derived from silica and silicate, starch, sugar, and inorganic salts. More preferred fillers for this invention are kaolinites, attapulgite clay, montmorillonite clays, synthetic silicas, synthetic sodium alumina silicate, synthetic magnesium silicate, calcium sulfate dihydrate, and disodium hydrogen phosphate.

Suitable surfactants for use in such compositions are those listed by J. W. McCutcheon in "Detergents and Emulsifiers" 1968 Annual. Among the most preferred surfactants are the nonionic and anionic type, and those most suitable for the preparation of the dry, soluble products of this invention are solid forms of compounds known to the art as wetters and dispersants. Occasionally a liquid, non-ionic compound classified primarily as an emulsifier may serve as both wetter and dispersant.

Most preferred wetting agents are alkylbenzene- and alkynaphthalene-sulfonates, sulfated fatty alcohols, amines or acid amides, long-chain acid esters of sodium isethionate, esters of sodium sulfosuccinate, sulfated or sulfonated fatty acid esters, petroleum sulfonates, sulfonated vegetable oils, ethylene oxide adducts of alkyl phenols and long-chain alcohols, and their phosphate derivatives, sorbitan fatty esters and their ethylene oxide adducts, and tertiary acetylenic glycols. Preferred dispersants are methylcellulose, polyvinyl alcohol, lignin sulfonates, polymeric alkynaphthalenesulfonates, sodium naphthalenesulfonate, polymethylene bisnaphthalenesulfonate, and sodium N-methyl-N-(long chain acids) taurates.

Wetting and dispersing agents in water-soluble compositions of this invention are usually present at concentrations up to about 5 weight percent. The inert ex-

tender then completes the formulation. Where needed, 0.1 weight percent to 1.0 weight percent of the extender may be replaced by a corrosion inhibitor or an anti-foaming agent or both.

Thus, water-soluble formulations of the invention will contain from about 25 to 95 weight percent active material, from 0 to 2.0 weight percent wetting agent, from 0 to 5.0 weight percent dispersant, and from 0 to 75 weight percent inert extender, as these terms are described above.

When the water-soluble powder contains a corrosion inhibitor or an anti-foaming agent or both, the corrosion inhibitor will not exceed about 1 percent of the composition, and the anti-foaming agent will not exceed about 0.5 percent by weight of the composition, both replacing equivalent amounts of the inert extender.

It will be understood that the compounds of formula (1) vary in degree of water solubility and that in some cases, such as concentrate spraying, it may be desired to use them in aqueous systems at concentrations above their solubility limit, i.e., as partially soluble wettable powders. Such use is possible provided the product has been ground sufficiently for use in the equipment and provided the spray mixture is not held so long that crystal growth leads to inseparability. In the latter case, crystallization inhibitors, such as protective colloids, can be of some help.

Solution Concentrates

The aqueous solution concentrates are prepared by mixing a water-soluble active compound of this invention with water. A portion of the water may be replaced with methanol, ethanol, isopropanol, ethylene glycol, cellosolve or methyl cellosolve. Surfactants and buffering agents can optionally be present.

These aqueous solution concentrates will contain from 15 to 50 percent of active ingredient, and from 50 to 85 percent water or mixture of water and hydroxylated organic solvent. Surfactants, corrosion inhibitors, buffering and anti-foam agents may also be included in which case they may replace up to 10 percent of the solvent system.

Dusts

Dusts are dense powder compositions which are intended for application in dry form, in accordance with the preferred compositions and methods of the invention. Dusts are characterized by their free-flowing and rapid settling properties so that they are not readily windborne to areas where their presence is not desired. They contain primarily an active material and a dense, free-flowing, solid extender.

Their performance is sometimes aided by the inclusion of a wetting agent, and convenience in manufacture frequently demands the inclusion of an inert, absorptive grinding aid. For the dust compositions of this invention, the inert extender may be either of vegetable or mineral origin, the wetting agent is preferably anionic or non-ionic and suitable absorptive grinding aids are of mineral origin.

Suitable classes of inert solid extenders for use in the dust compositions are those organic or inorganic powders which possess high bulk density and are very free-flowing. They are also characterized by possessing relatively low surface areas and are poor in liquid absorption. Suitable classes of grinding aids are natural clays, diatomaceous earths, and synthetic mineral fillers derived from silica or silicate. Among ionic and non-ionic

wetting agents, the most suitable are the members of the group known to the art as wetting agents and emulsifiers. Although solid agents are preferred because of ease in incorporation some liquid non-ionic agents are also suitable in the dust formulations.

Preferred inert solid extenders for the dusts of this invention are micaceous talcs, pyrophyllite, dense kaolin clays, tobacco dust and ground calcium phosphate rock such as that known as "Phosphodust," a trademark of the American Agricultural Chemical Company.

Preferred grinding aids are attapulgite clay, diatomaceous silica, synthetic fine silica and synthetic calcium and magnesium silicates. Preferred wetting agents are those previously described under water-soluble powder formulations.

The inert solid extenders in the dusts of this invention are usually present in concentrations of from about 30 to 90 weight percent of the total composition. The grinding aid will usually constitute 5 to 50 weight percent of the composition, and the wetting agent will constitute from about 0 to 1.0 weight percent of the composition. Dust compositions can also contain other surfactants such as dispersing agents in concentrations of up to about 0.5 weight percent.

The water-soluble powders described above can also be used in the preparation of dusts. While such water-soluble powders could be used directly in dust form, it is more advantageous to dilute them by blending with the dense dust diluent. In this manner, dispersing agents, corrosion inhibitors, and anti-foam agents may also be found as components of a dust.

Thus, the dust compositions of this invention will comprise about 5 to 20 weight percent active material, 5 to 50 weight percent adsorptive filler, 0 to 1.0 weight percent wetting agent, and about 30 to 90 weight percent dense, free-flowing dust diluent, as these terms are used herein. Such dust formulations can contain, in addition, minor amounts of dispersants, corrosion inhibitors, and anti-foam agents, derived from the water-soluble powders used to make the dusts.

Granules and Pellets

Under some circumstances it may be advantageous to apply the compounds of this invention in the form of granules or pellets. Suitable carriers are natural clays, some pyrophyllites and vermiculites. Wetting agents of the type listed by J. W. McCutcheon in "Detergents and Emulsifiers" 1967 Annual can also be present to aid leaching of the active component.

One method of preparation suitable for both granules and pellets involves blending the active ingredient with clays, water-soluble salts, surfactants and a small amount of water. After pelleting and/or granulating, the formulation is dried prior to use. A second method suitable for the preparation of granules formulation involves spraying a solution of the active material on porous, adsorptive, preformed clay or vermiculite granules. Preformed granules of organic origin, such as corn cob, are also suitable for use by this method of preparation. Surfactants listed by McCutcheon can also be included in the spray solution. After drying, the granules are ready for application.

The preferred granules or pellets will contain about 5 to 30 weight percent of active material, about 0 to 5 weight percent wetting agent and about 65 to 95 weight percent inert mineral carrier.

Paints and Dressings

While the formulations described above can be used to apply the compounds of formula (1) to cut portions of plants, these compounds can also be included in paints and tree-wound dressing to be applied to local areas after pruning.

Thus, taking advantage of good water-solubility, they can be incorporated in various aqueous emulsions of asphalt or in water-based paints. Aerosol paint formulations can be of the water-in-oil emulsion type, usually with organic soluble propellant and film former, or may be an aqueous system propelled by inert gas.

Alternatively, the compounds may be finely divided and dispersed in organic systems such as organic solvent based paints and varnishes. It is preferred to use relatively nonpolar solvents, such as aliphatic hydrocarbons, in such systems to prevent crystal growth in storage. Such formulations have the disadvantage that they must be well stirred before use to insure accurate dosing. This requires some care, as relatively low levels of active ingredient are present.

Certain compounds of formula (1), particularly those having large organic substituents, have sufficient solubility in organic solvents to permit formulation in organic solutions for application to cut portions of plants.

Thus, they may be incorporated into organic solvent based paints, lacquers, and varnishes at relatively low, but effective, levels. These may be of the type designed for aerosol or bough application. For this purpose halocarbon and aromatic hydrocarbon solvents are preferred, but other more polar solvents, such as ketones, alcohols, ethers, esters and amides can be included as cosolvents or as sole solvents.

Application

As stated earlier, this invention is founded on the discovery that the compounds of formula (1) are useful for modifying the growth rate of plants. More particularly the compounds of this invention are useful as plant growth retardants. They also affect the flowering and fruit set of numerous plants.

The term plant growth retardant as used in this disclosure is to be understood to mean an agent which when applied to a plant or its environs will slow the growth of the plant. This also includes a delaying response on bud sprouting or prolonging of the dormancy period.

The compounds of this invention can be used to retard the growth of woody vegetation. The compounds of this invention can also be used to control the growth of turf and other herbaceous vegetations.

The compounds of this invention can be applied as foliar sprays or as soil applications to retard the growth rate of such plants or to affect flowering and fruit set.

Preferably, the compounds of this invention are applied as a foliar spray to the point of runoff although lower-volume application may also be effective.

It is preferred that the application be made while the buds for next years growth are developing, but application can also be made during the dormant stage or just after the plants have been trimmed. Or if flowering and fruit set are to be modified, the treatment is applied before, during or shortly after flowering.

It will be recognized that the rate of application is dependent upon the species to be treated and the results desired. In general, rates of from 0.25 to 20 kilograms per hectare are used although higher or lower rates can achieve the desired effect in some instances. Preferably

the composition will be applied at the rate of from 1 to 10 kilograms per hectare.

It will also be appreciated that there are a number of methods that can be used for applying the active compound to the plant. Spray application being the most convenient, is therefore the most commonly used method. The compositions can be sprayed from air or ground carriers. In the application of the active compound particular attention should be given to thorough and uniform coverage of the plants treated to obtain the desired results.

The following Examples are presented to further illustrate the formulation and application of the compounds of this invention. Parts and percentages in the following examples are by weight unless otherwise indicated.

EXAMPLE 45

A dust having the following formula is prepared.

Ethyl carbamoyl-N,N-diethylphosphonamidate	5.0%
Talc	64.0%
Attapulgite	30.0%
Sodium benzenesulfonate	1.0%

The active component is ground with the minor diluent and the surfactant to pass a 0.149 mm. screen. This material is then blended with the major diluent to form a dust composition.

The following compounds of this invention can be formulated in like manner.

Allyl carbamoyl-N,N-dimethylphosphonamidate

2-Chloroethyl carbamoyl-N,N-diethylphosphonamidate

Methyl carbamoyl-N,N-diethylphosphonamidate

Isopropyl carbamoyl-N,N-diethylphosphonamidate

Methyl carbamoyl-N,N-diallylphosphonamidate

Twenty kilograms of the above formulations was applied to a power line right-of-way area of approximately 1 hectare. Oak (*Quercus spp.*), Maple (*Acer spp.*), Sweetgum (*Liquidamborstylaciflora*), pine, (*Pinus spp.*), and locust (*Robinia pseudoacacia*) were among the predominant woody species growing in this area. The treatment effectively retarded the growth rate of these plant species and reduced cost of maintaining desirable green, low-growing vegetation on the right-of-way.

EXAMPLE 46

A water-soluble powder of the following formula is prepared.

Allyl carbamoyl-N,N-dimethylphosphonamidate	95.0%
Synthetic silica	3.5%
Disodium hydrogen phosphate	1.0%
Diocetyl sodium sulfosuccinate	0.5%

The above ingredients are mixed and then ground to pass a 0.42 mm. screen. The resulting formulation is water-soluble powder, with the exception of the synthetic silica conditioning agent.

The following compounds of this invention can also be formulated in like manner.

Ethyl carbamoyl-N,N-diethylphosphonamidate

2-Chloroethyl carbamoyl-N,N-diethylphosphonamidate

Methyl carbamoyl-N,N-diethylphosphonamidate

Methyl carbamoyl-N,N-dimethylphosphonamidate

Isopropyl carbamoyl-N,N-diethylphosphonamidate

Six kilograms of the above formulation are dissolved in 800 liters of water and sprayed over a hectare of brush along a railway right-of-way in August. The treatment has no effect on the brush the year of application, but the next spring delays bud break and retards the growth of the brush. Meanwhile, the grasses and other low growing vegetation flourish underneath the brush giving a desirable green ground cover underneath.

EXAMPLE 47

A wettable powder of the following formula is prepared.

Ethyl carbamoyl-N,N-dimethylphosphonamidate	50.0%
Montmorillonite	43.0%
Synthetic silica	4.0%
Disodium hydrogen phosphate	1.0%
Sodium alkylnaphthalenesulfonate	1.0%
Sodium lignin sulfonate	1.0%

25

The above ingredients are mixed and then ground to pass a 0.25 mm. screen. The active ingredient in the above formulation dissolves when the composition is added to water.

The following compounds can be formulated in like manner.

Allyl carbamoyl-N,N-dimethylphosphonamidate

2,2,2-Trichloro carbamoyl-N,N-diethylphosphonamidate

Propargyl carbamoyl-N,N-dimethylphosphonamidate

Isopropyl carbamoyl-N,N-diethylphosphonamidate

Methyl carbamoyl-N,N-diethylphosphonamidate

Octyl carbamoyl-N,N-dimethylphosphonamidate

Twenty kilograms of the above wettable powder are suspended in 1,000 liters of water and applied in early September to the brush growing on 1 hectare of area surrounding a television relay tower on top of a mountain. The treatment has no effect on the brush for the remainder of the season; however, in the spring the bud break is prevented or delayed, and the growth of the brush is retarded. The grasses and other low growing vegetation are unaffected and covers the area preventing erosion and keeping the area green.

EXAMPLE 48

A solution of the following formula is prepared.

Methyl carbamoyl-N,N-diallylphosphonamidate	24.0%
Disodium hydrogen phosphate	1.0%
Sodium laurylsulfate	0.5%
Water	74.5%

55

The above components are blended to form a homogeneous solution.

The following compounds can be formulated in like manner.

Ethyl carbamoyl-N,N-diethylphosphonamidate

2-Chloroethyl methylcarbamoyl-N,N-diethylphosphonamidate
